UNITED STATES PATENT OFFICE.

WILLIAM C. JOHNSON, OF MINNEAPOLIS, MINNESOTA.

SEAL-TIGHT ROOFING CLEAT.

Application filed July 24, 1922. Serial No. 576,918.

To all whom it may concern:

Be it known that I, WILLIAM C. JOHNSON, a citizen of the United States, residing at Minneapolis, in the county of Hennepin and 5 State of Minnesota, have invented certain new and useful Improvements in Seal-Tight Roofing Cleats; and I do hereby declare the following to be a full, clear, and exact 10 description of the invention, such as will enable others skilled in the art to which it appertains to make and use the same.

This invention relates to a roof made of overlapping sheets of roofing material and particularly to a cleat adapted to be used 15 with such a roof. Roofs are now commonly covered with sheets of material comprising various waterproof and weather resisting substances such as asphaltum, and the like. Such sheets are usually placed 20 on the roof with the edges in overlapping relation, and such overlapping edges fastened with nails or staples. Under action by the weather, such roofing expands and contracts more or less and the fastening 25 means or nails are lifted somewhat. The moisture often gets under the nail heads and finds its way to the interior of the roof through the nail holes, thus damaging the roof and producing leaks.

30 It is an object of this invention to provide a cleat covering the edge of the overlapped layer and also adapted to cover the nails or fastening means.

It is more specifically an object of the invention to provide such a cleat comprising 35 a strip of sheet material bent at one edge to contact the edge of the overlapped roofing sheet and having its other edge bent upon itself to cover the fastening means extending 40 through the cleat.

These and other objects and advantages of the invention will be fully set forth in the following description made in connection with the accompanying drawings, in 45 which like reference characters refer to the same parts throughout the different views, and in which

Fig. 1 is a plan view of a portion of the roof showing the cleat applied thereto; and 50 Fig. 2 is a vertical section taken substantially on the line 2—2 of Fig. 1, as indicated by the arrows.

Referring to the drawings, a portion of a roof is shown comprising a base portion 55 formed of boards 1 placed adjacent each other and which will be supported on the

roof studding. These boards may, if desired, be provided with interlocking tongues and grooves, as shown in Fig. 2. On this base are laid the sheets 2 of the roofing material, the lower edges of said sheets overlapping the upper edges thereof throughout the extent of the roof. The sheets are fastened to the roof base by fastening means illustrated as nails 3 which pass through the overlapped portions of the sheets. In accordance with the present invention, a cleat 60 designated generally as 4 is provided. This cleat is formed with a strip or sheet of material preferably sheet metal, such as galvanized iron, adapted to extend along and adjacent the edge of the overlapping sheet 65 2. The nails 3 are driven through the cleat, as shown in the drawings, said nails being spaced at suitable distances to properly hold 70 the sheets. The nails may be driven through holes provided in the cleat, or as the cleat is of comparatively thin material, the nails may puncture the same when driven. The cleat has one edge 5 thereof 75 illustrated as the lower edge bent to extend substantially at right angles to the main portion of the cleat which receives the fastening means, and this edge is adapted to overhang and contact with the edge of the 80 overlapping sheet. In making this bend a small bead 6 is formed extending longitudinally of the cleat. The other edge 7 of the cleat is first bent upwardly, as shown in the 85 upper part of Fig. 2, and after the nails 3 are driven in place, the edge is bent downwardly on the body portion 4 of the cleat in substantially parallel relation thereto and has its lower edge positioned substantially 90 in contact with said body portion, as shown in the lower part of Fig. 2. The strips 4 will be made in appropriate lengths and abut, end to end, as shown in Fig. 1. In practice, it has been found that the length 95 of about twenty four inches is a convenient 100 length for said cleats.

While the cleat has been illustrated as applied to the sheet 2 extending transversely of the roof 1 the plate can be used on roofing in which the sheets extend vertically or up 105 and down on the roof. In some cases it is more convenient to have the length of the sheets 2 which commonly come in rolled form, running up and down. The down-turned edge 5 forms a means for quickly 110 and properly positioning said cleat.

From the above description it is seen that

applicant has provided a simple and efficient roof cleat. By the use of this cleat the edge of the roofing sheet is protected and the fastening means are entirely covered. The 5 cleat presses tightly against the roofing sheet and forms a tight seal therewith. The damaging effect of the weather on the attaching portions of the sheet are thus effectively overcome. The cleat has been 10 found to be very efficient and effective in actual practice.

It will, of course, be understood that various changes may be made in the form, details and proportions of the device without 15 departing from the scope of applicant's invention, which, generally stated, consists in the matter shown and described and set forth in the appended claims.

What is claimed is:

20 1. The combination with overlapped sheets of roofing material, of a cleat extending along and adjacent the edge of the overlapping sheet and having one edge thereof bent substantially at a right angle to over- 25 hang said edge of the sheet, said cleat receiving the fastening means in the roofing sheets, and having its other edge bent over to cover said fastening means.

2. The combination with overlapped 30 sheets of roofing material, of a cleat formed

of a strip of sheet material and extending along adjacent the edge of the overlapping roofing sheet, said cleat receiving the fastening means therethrough and having one edge bent over parallel to the main portion 35 thereof to cover such fastening means.

3. The combination with overlapped sheets of roofing material, of a cleat having its edge bent to overhang and contact with the edge of the overlapping sheet and having 40 a raised bead at said bend, said cleat having fastening means passing therethrough and having its other edge bent over on its main portion to cover said nails.

4. A cleat for sheet roofing comprising a 45 strip of sheet metal bent closely adjacent one edge at substantially a right angle and having its other edge bent over on itself to form a cover for fastening means passing through said cleat.

5. A cleat for sheet roofing comprising a strip of sheet metal bent closely adjacent one edge at substantially a right angle and having a curved bead adjacent said bend and having its other edge bent over and substantially parallel with the body of said strip.

In testimony whereof I affix my signature.

WILLIAM C. JOHNSON.
